WRECKING BAR

Jimmie Marson, Rte. 2, Box 224, Wewoka, Okla.

Filed Dec. 3, 1962, Ser. No. 72,676

Term of patent 14 years

(Cl. D93—4)

FIG. 1 is a side elevational view of a wrecking bar embodying my new design;

FIG. 2 is a front elevational view thereof;

FIG. 3 is a top plan view thereof.

The characteristic features of my design reside in the specific configuration of the fulcrum and bar and their offset relationship, as shown.

I claim:

The ornamental design for a wrecking bar, as shown and described.
